SLIDABLE SIDE JAW SOCKET WRENCH

Johan Pehrsson, Stockholm, Sweden

Application May 21, 1947, Serial No. 749,540

2 Claims. (Cl. 81—126)

1

This invention relates to slidable side jaw sockets wrenches with a stationary jaw and an adjustable jaw the distance between the jaws being adjustable by means of a worm or screw.

The primary object of the invention is the provision of means whereby the wrench in a simple and efficient manner only by reverse movement of the wrench handle or by such movement in combination with a simple opening grip by hand will obtain a new grip on the work without the necessity of removing the wrench from the work. Another object is to provide a wrench of said kind assuring a firm and secure grip of the wrench on the work. A further object is the provision of means which will prevent unintentional movement or play of the adjusting worm.

These and other objects of the invention will be made clear by the following description with reference to the accompanying drawing illustrating an embodiment of the invention. In the drawing, Figs. 1 and 2 are side elevations of the wrench, a cover plate being removed from the head of the wrench according to Fig. 1. Fig. 3 is a side view of the head portion of the wrench. Fig. 4 is a section on the line IV—IV of Fig. 2. Fig. 5 shows a fragmentary section on the line V—V of Fig. 2.

The wrench comprises a head 1 and a handle 2, and this handle is pivoted to the head by a pin 3. A cover plate 4 is attached by rivets to the head 1. One of these rivets also serves as pivot 3 for the handle 2, another rivet serves as clamping pin 6 for a leaf spring 7, and still another rivet serves as supporting pin 5 for the handle 2. As is usual the wrench head 1 is provided with a stationary jaw 8 and a movable jaw 9, the latter being adjustable towards and from the stationary jaw 8 by a screw or worm 10 engaging a rack portion 9' of the movable jaw 9. Worm 10 is rotatably journalled in the head 1 on a carrying shaft or spindle 12 which is slidable longitudinally in suitable guide ways 11 in the head 1 (Fig. 1) in the directions of movement of the adjustable jaw 9, but not rotatable in the head. One end portion of the shaft 12 (the link portion according to Fig. 1) engages directly with the guide ways 11 of the head 1, and this end portion is provided with a recess 13 with which a tooth or projection 14 on the end of the handle 2 permanently engages. This permanent articulated connection may, of course, also consist of several teeth or a toothed segment engaging with corresponding recesses or a rack formed on the shaft 12. The portion of the shaft 12 at the opposite end of the worm 10 engages indirectly

with the guide ways 11 of the head 1 by means of a sleeve or socket 15 on said portion of the shaft. This sleeve or socket is slidable together with the carrying shaft 12 but not rotatable in the guide ways. The extreme or right end of the socket 15 is recessed to receive a coil spring 16 which by means of a nut 17 on the adjacent threaded end of the shaft 12 is forced against the socket 15 which, in turn, is forced against the worm 10. Thus, the socket 15 will exert a permanent braking pressure on the worm 10 so that in use of the wrench unintentional rotation of the worm and loosening of the grip of the wrench on the work is prevented. Between the head 1 and handle 2 a leaf spring 7 (Fig. 1) is provided tending to hold the handle 2 in contact with the stop pin 5 or other stop member in the head 1 for obtaining a suitable position of the head 1 in relation to the handle 2 in the adjustment of the distance between the jaws, for a grip on the nut or screw and in reverse movement when a new grip on the nut or screw is to be taken. One end portion of the leaf spring 7 is forced against the handle 2 and the other end portion of the spring is clamped between the pin 6 and a pin 18 in the head 1. This latter pin 18, engaging with the extreme end of the spring, is provided with screw threads engaging with corresponding threads in a hole in the cover plate 4 as shown particularly by Fig. 5. Thus the pin 18 may be easily removed if the leaf spring 7 must be replaced by a new one. The end portion of the handle 2 adjacent to the shaft 12 (Fig. 1) is provided with a stop surface 19 adapted to contact with the shaft 12 in a certain position of the handle. The position of the stop surface 19 in relation to the shaft 12 determines the size of the greatest reverse movement of the handle 2. The head 1 including the cover plate 4 is extended rearwardly in the longitudinal direction of the handle 2 and this rear extension which may be of various lengths, terminates in a tongue 20 for opening by hand if such is desired. The tongue 20 extends somewhat laterally of the handle 2 for movement of the head 1 by the operator's hand or finger until the stop pin 5 contacts the handle, if such manual operation of the head is desired. The head 1 with the cover plate 4 is provided with bevelled surfaces (Figs. 2 and 4) about the worm 10 which enable a good grip for the operator when the opening between the jaws is to be adjusted by rotation of the worm.

The pivot pin 3 of the handle 2 in different sizes of the wrench is so located that the handle

2 forms a lever of a certain length. Obviously the two jaws of the wrench in the operation thereof for tightening of a nut or screw are actuated by forces that are directed opposite to each other.

The handle lever should be of such a length that the resultant of these forces, which actuate the adjusting member 10 in operation only by means of the handle or by means of the handle and the head in the grip on the nut or screw in the calculated greatest strain for sliding apart of the jaws, is equal to zero or more than zero with the excess of the force acting in the adjustment direction of the movable jaw 9 towards the stationary jaw 8.

The supporting or stop pin 5 in the head 1 is so located in relation to the pivot pin 3 of the handle 2 that these two pins in cooperation will prevent the handle 2 from jamming the worm 10 in the head 1 whereby the adjustments will be easily effected. Said pins also hold the handle 2 in such a normal or resting position in relation to the head 1 that the wrench will be strong and durable should the wrench be used as a hammer since in such use the strains will be taken up by the two pins.

As is evident by the description, after a turning of the nut or screw by the wrench the opening between the jaws can be increased in a simple and efficient manner by reverse movement of the handle 2 which by the shaft 12 and the adjusting worm 10 moves the jaw 9 so that the jaws 8, 9 can be moved past the corners of the nut or the screw head and cause the jaws to get a new grip on the work which can be tightened up or loosened continuously.

In the embodiment shown the invention is applied to a wrench in which the adjustable jaw 9 is movable in a direction forming an angle to the longitudinal direction of the handle lever 2, but it is evident that the invention also may be applied to a wrench the adjustable jaw of which is movable substantially parallel with the longitudinal direction of the handle 2. Thus, the invention is not restricted to wrenches in which the distance between the jaws is adjustable substantially in the transverse direction of the handle 2. Also other details of the wrench may be varied without departing from the spirit of the invention.

What I claim is:

1. A wrench comprising in combination, a head; a stationary jaw formed on said head; a single handle constituting a lever; an angular guideway formed in said head; a shaft axially slidably in said guideway; two angular portions disposed at either end of said shaft so as to lock

the same against rotation, the first of said angular portions formed with an end recess in its outer end, and the second of said angular portions formed with a lateral recess in a lateral face

5 thereof; a worm rotatably mounted on said shaft intermediately of said angular portions; a slideable jaw; a thread formed on said slideable jaw and being engaged by said worm for adjustment of the slideable jaw relatively to the stationary jaw; a coil spring extending into said recess in said first angular portion and acting against the latter so as to force it against said worm to prevent undesired rotation of the latter; a projection formed on the inner end of said handle, 10 the said projection extending into said lateral recess in said second angular portion; and means 15 for swingably supporting said handle on said head whereby said shaft, worm and slideable jaw may be moved toward and away from said stationary jaw by mere swinging of the handle relatively to the head.

2. A wrench comprising in combination, a head; a stationary jaw formed on said head; a single handle constituting a lever; a shaft locked 20 against rotation and axially slidably associated with said head and extending at an angle to said handle; a worm rotatably mounted on said shaft; a slideable jaw; rack teeth formed on said slideable jaw and being engaged by said worm for adjustment of the slideable jaw relatively to the stationary jaw; means for swingably supporting said handle on said head; a stop provided on said head; two spaced pins provided on said head; a leaf spring being clamped with one of its ends 25 between said spaced pins so as to be in abutment with its major faces with the lateral faces of said pins, the other end of said leaf spring engaging said handle so as to resiliently force it against said stop; and an articulated connection between said handle and said shaft whereby said shaft, worm and slideable jaw may be moved toward and away from said stationary jaw by mere swinging of the handle relatively to the head.
